UNITED STATES PATENT OFFICE

2,118,638

SEALING DEVICE FOR METERS

Hans A. Bakke, Swampscott, Mass., assignor to
General Electric Company, a corporation of
New York

Application July 29, 1936, Serial No. 93,218

7 Claims. (Cl. 171—34)

My invention relates to sealing arrangements and concerns particularly arrangements for sealing electric integrating meters.

It is an object of my invention to provide a simple, relatively inexpensive but sturdy and reliable arrangement for sealing covers on casings.

A further object of my invention is to provide such an arrangement for both sealing a cover on the terminal chamber of an electric meter and sealing the locking arrangement for the cover of the meter mechanism.

Other and further objects and advantages will become apparent as the description proceeds.

In accordance with my invention in its preferred form, I provide a terminal chamber cover for an electric meter with a sliding bar for covering screws adapted to fasten the cover to the meter casing. The sliding bar is adapted to be sealed by sealing wire or other suitable seal when in its sealed position and to uncover said fastening screws when in its unsealed position.

My invention will be understood more readily from the following detailed description when considered in connection with the accompanying drawing and the features of my invention which are believed to be novel and patentable will be pointed out in the claims appended hereto. In the drawing, Fig. 1 is a front elevation of an electric integrating meter employing a sealing arrangement forming an embodiment of my invention; Fig. 2 is a cross-sectional view of the terminal chamber of the apparatus of Fig. 1 cut by the plane 2—2; and Fig. 3 is an exploded perspective view of the arrangement of Fig. 1 showing the cover removed from the terminal chamber and the cover sealing bar in its unsealed position. Like reference characters are utilized throughout the drawing to designate like parts.

Referring now more in detail to the drawing, the meter to which my invention is applied is shown as one of conventional design having a base 11 with a chamber for receiving the meter mechanism enclosed by a cup-shaped glass cover 12, and a terminal chamber 13 adapted to be closed by a cover 14.

The cup-shaped cover 12 is of conventional design having a bayonet lock for fastening it in position by a twisting motion. Such bayonet locks are well known and consist of a plurality of slots and cooperating pins, one of which is shown at 15 in Fig. 3. A sliding bar arrangement, such as that described more in detail in my Patent No. 1,979,928, is provided for locking the cover 12 in position and consists of a locking bar 16

with a nose 17 adapted to engage a projection 18 on the rim of the cover 12, thus preventing its being untwisted and removed when the locking bar 16 is in the locked position. The locking bar 16 has a slot adapted to slip over a lug 19 with an opening for receiving a sealing wire 20 when it is desired to seal the chamber for the meter mechanism independently of the terminal chamber.

In the drawing, I have shown only a portion 10 of the cover 14 serving to enclose the terminal chamber 13. It will be understood that my invention is not limited to the specific arrangement shown but includes the use of my novel seal in connection with a cover for closing both a terminal chamber and a connection box. The side walls 21 and 22 of the terminal chamber 13 are provided with tapped holes 23 and 24 for receiving cover-fastening screws. The cover 14 is provided with corresponding screw holes 25 and 26 for receiving screws 27 and 28. Preferably, the screw holes 25 and 26 are counterbored as shown in Fig. 2 to permit the heads 29 and 30 to drop below or come flush with the surface of the cover 14.

For covering the screw holes 25 and 26 in the cover 14, a sliding sealing bar 31 is provided. To receive the sliding bar 31, there is a longitudinal groove 32 in the cover 14 in line with the screw holes 25 and 26 in order that the bar 31 may be placed in position to cover the screw holes 25 and 26. Preferably, the cover is so formed that, at the ends of the groove 32, there are projecting portions 33 with slots 34 through which the bar 31 may slide and which may prevent the bar 31 from being pulled away from the cover 14 out of the groove 32. The sealing bar 31 is provided with an opening 35 so positioned as to uncover the left-hand screw hole 25 when the bar 31 is moved far enough to the left so that its right-hand end 36 uncovers the screw hole 26. A stop 37, which may take the form of a projection at the left-hand end of the bar 31, is provided to prevent the bar 31 from being slipped out of the groove 32 by sliding the bar to the right, and the right-hand end 38 of the bar 31 is provided with an opening 39 adapted to receive a sealing wire 39 or other suitable type of seal to prevent the sealing bar 31 from being moved to the left without giving evidence that the seal has been broken and the meter has been tampered with.

It is evident that, when the sealing bar 31 is in the right-hand position shown in Fig. 1, if the screw holes 25 and 26 are covered, it is

impossible to unscrew the screws 27 and 28 or to remove the cover 14 from the terminal chamber 13. Inasmuch as the conductors for making connection to the meter are secured by means 5 of terminal screws 48 within the terminal chamber 13, the sealing of the terminal chamber cover 14 also prevents the conductors from being removed from the meter and prevents electrical connections from being made to the meter or to 10 the conductors without mutilating either the meter or the insulation on the conductors and giving evidence that the apparatus has been tampered with.

Furthermore, the cover 14 is provided with 15 flanges 41 which overhang the terminal chamber 13 to prevent instruments from being inserted between the cover 14 and the edges of the terminal chamber 13 and to prevent the locking bar 16 from being moved out of its locked position. A single sealing wire 29 inserted in the sliding bar 31 consequently serves to seal both 20 the terminal chamber 13 and the chamber containing the meter mechanism enclosed by the cover 12.

25 The case 11 is provided with screw holes 42 to receive screws (not shown) for fastening the apparatus to a wall or panel, and the cover 14 is provided with overhanging extensions 43 reinforced with ribs 44 in order that the sealing 30 in place of the cover 14 will also serve to seal the meter in position on the panel or wall where it is mounted. In this way, attempts to tamper with the meter mechanism or wiring by detaching the meter are discouraged.

35 I have described a construction having the stop 37 to prevent slipping the sealing bar 31 out of its groove 32 and having the slotted projecting portions 33 and 34 to prevent pulling the sealing bar forward away from the cover 14. It 40 will be understood, however, that my invention is not limited to this precise construction but obviously includes other arrangements for preventing removal of the sealing bar 31. If desired, the sliding bar 31 may be provided with 45 an elongated slot 45 and the cover 14 may be provided with a rivet 46 cooperating with the elongated slot 45 to limit the extent of sliding of the sealing bar 31 in either direction and to prevent removal thereof. The stop 37 may be 50 omitted when the rivet 46 is employed but it will be apparent that the retention of both means for limiting the travel of the sealing bar 31 serves to provide maximum protection against undetected tampering with the apparatus.

55 In accordance with the provisions of the patent statutes, I have described the principle of operation of my invention together with the apparatus which I now consider to represent the best embodiment thereof but I desire to have it 60 understood that the apparatus shown is only illustrative and that the invention may be carried out by other means.

What I claim as new and desire to secure by Letters Patent of the United States is:

65 1. In combination, a meter casing with a terminal chamber having side walls and an open front, a cover for said terminal chamber, and a sealing bar for said cover, said side walls having holes threaded to receive screws for fastening said cover to said terminal chamber, and said cover having screw holes cooperating with the threaded holes in said side walls, said cover having a groove for slidably receiving said sealing bar, said groove being in line with said screw holes, said bar having a stop for limiting its

motion to an extreme position in one direction, and being of such length as to protrude from said cover when in the extreme position permitted by said stop, and having an opening in the end thereof protruding from said cover when 5 the bar is slid in said extreme position, said bar normally covering said screw holes and preventing access to the screws therein but having an opening for exposing one of said screw holes when slid away from said extreme position far enough for its end to uncover the other of said screw holes.

2. A sealing arrangement for a meter having a terminal chamber and a slidable locking bar adapted to lock a meter chamber, said sealing arrangement comprising a cover adapted to close said terminal chamber and having a flange overhanging said locking bar when the latter is in its locking position, screws for fastening said cover to said meter over said terminal chamber, 20 and a sealing bar supported on the cover slideable between sealing and unsealed positions, said cover having screw holes adapted to receive said screws, the sealing position of said sealing bar being over said screw holes, said sealing bar being adapted to be moved to an unsealed position, uncovering said screw holes, and having means for sealing it in said sealing position.

3. A sealing arrangement for a meter casing having a terminal chamber, a slidable locking bar adapted to lock a meter chamber, and mounting-screw holes near the edges of said terminal chamber, said sealing arrangement comprising a cover adapted to close said terminal chamber, having a flange overhanging said locking bar 35 when the latter is in its locking position, and having extensions covering said mounting screw holes, screws for fastening said cover to said casing over said terminal chamber, a sealing bar supported on the cover slideable between sealed 40 and unsealed positions, and means for sealing said sealing bar in a sealed position, said cover having screw holes adapted to receive said cover-fastening screws, the sealed position of said sealing bar being over said cover-fastening screw 45 holes, and said sealing bar being adapted to be moved to an unsealed position uncovering said screw holes.

4. In combination, a chamber sealing cover with screw holes adapted to receive screws for 50 fastening said cover, and a sealing bar slideable on said cover in one direction to a sealed position covering said screw holes and slideable in the opposite direction, said cover having a groove for receiving said sealing bar and means for 55 holding the bar slidably in said groove, said bar being adapted to fill the groove, having a stop for limiting motion in one direction to the sealed position and being of such length as to have an end protrude from said cover when the bar 60 is in the sealed position, said protruding end having an opening for receiving a sealing device.

5. In combination, a chamber sealing cover with screw holes adapted to receive screws for 65 fastening said cover, and a sealing bar slideable on said cover in one direction to a sealed position covering said screw holes and slideable in the opposite direction, said cover and bar including means for limiting motion of the bar in the 70 former direction, said bar being of such length as to have an end protruding from said cover when in the sealed position, and having an opening in said end adapted to receive a sealing device, and having a second opening so placed as 75

to register with one of said screw holes when the bar is moved sufficiently away from its sealed position for the end thereof to travel beyond and uncover the second of said screw holes.

5 6. A meter-sealing arrangement comprising in combination with a terminal chamber in a meter casing having tapped holes at the edges of said terminal chamber, a terminal chamber cover, cover-fastening screws, and a sealing bar with
10 means for sealing it in a sealed position, said cover having a longitudinal groove therein with screw holes in said groove registering with said tapped holes for receiving said screws to fasten said cover over said terminal chamber, said sealing bar being slidably supported in said groove,
15

being adapted to fill the groove, having a sealed position in which the bar covers said screw holes, and being slidable from said position to uncover said screw holes.

7. In combination, a chamber-sealing cover 5 having a longitudinal groove therein with screw holes in said groove adapted to receive screws for fastening said cover, and a sealing bar with means for sealing it in a sealed position on said cover covering said screw holes, said sealing bar 10 being supported in said groove, being adapted to fill the groove and being slidable from said sealed position for uncovering said screw holes.
